UNITED STATES PATENT OFFICE

KENNETH LYLE, OF PHILADELPHIA, PENNSYLVANIA, ASSIGNOR TO BAYUK CIGARS INCORPORATED, OF PHILADELPHIA, PENNSYLVANIA, A CORPORATION OF MARYLAND

CIGAR-BRUSHING MACHINE

Application filed December 30, 1927. Serial No. 243,502.

This invention relates to a machine adapted to remove objectionable matter from the surface of a cigar.

It is found that when cigars are stored for a time there appears on the surface a growth of fungus consisting of a powder which, while harmless, gives the cigars an objectionable appearance. Heretofore, it has been customary to brush this material from the surface of the cigar by hand, and an object of the present invention is the provision of a machine of simple character which will effectively and rapidly remove such material from the surfaces of cigars, since the hand operation is necessarily slow, requiring a rotation of the cigar to effect a complete brushing.

In the accompanying drawing:

Figure 1 is a plan view of the improved machine;

20 Figure 2 is a vertical longitudinal section of the machine taken through the cigar guiding means; and

Figure 3 is a front elevation of the machine with the part of the guiding frame broken away.

In the drawings which illustrate a preferred embodiment of the invention, there are shown frame members 2 and 4, suitably secured to a table or other support, connected 30 together by means of horizontally extending rods 6 on which is mounted, by means of bosses 8 and 10, a movable frame 12 which may be adjusted along the rods 6 and held in a desired adjusted position by means of a wing 35 nut 14. Frame 12 is provided with a flaring guide mouth 16, through which cigars may be guided into contact with suitably placed brushes.

As shown most clearly in Figs. 2 and 3, 40 there are two sets of brushes 18 provided in the improved mechanism supported by downwardly extending members 20, carried by frame 12. Each set of brushes 18 consists of four brushes located as shown in Fig. 3 and rotatably mounted in depending mem-

bers 20, the axes occupying positions at the corners of squares leaving central openings between the brushes through which a cigar may be moved, the brushes being set close enough together to cause a contact of the 50 bristles thereof with the cigar. Members 20 are suitably apertured to provide for the passage of the cigar.

Extending horizontally between frame members 2 and 4 and rotatably mounted 55 therein, are pairs of brushes 22 and 24, each pair consisting of an upper and a lower brush geared together through pinions 26 and 28, brushes 22 extending through frame 12 between the guide mouth thereof and the adjacent group of brushes 18, while the second pair of brushes 24 extend between the two groups of brushes 18. Any suitable means may be provided for rotating brushes 22 and 24, and as shown, a pulley 30 is secured to 65 the shaft of lower brush 22, upper brush 22 carrying on the shaft thereof a sprocket wheel 32 which is connected to a sprocket wheel 34 secured on the shaft of upper brush 24 by means of a chain 36. Any suitable 70 source of power may drive pulley 30 and from the connection just described, brushes 22 and 24.

As shown in the drawings, it is desirable to rotate brushes 22 and 24 at different speeds, 75 and hence sprocket wheel 32 is larger than sprocket wheel 34 whereby a differential feed of the cigar 40 by the brushes is secured.

In operation, a cigar 40 may be introduced into guide mouth 16 until it is engaged by the 80 bristles of brush 22 whereby it is yieldingly fed without crushing through the center of the first group of brushes 18, thence between brushes 24 and through the center of the second group of brushes 18, after which it is 85 discharged from the machine. By providing brushes having light bristles, a slight brushing action is given to the cigar, which effectively removes any objectionable surface material. It will be observed that 90

brushes 18 are stationary during the brushing of a cigar, their pivotal mounting being primarily for the purpose of moving them to positions to present new bristles to the cigars when the old ones have become worn. 5 To present new bristles of brushes 22 and 24 to cigars it is only necessary to adjust frame 12 along horizontal members 6.

While there has been described a machine 10 which is found to effectively remove all surface adhering matter from a cigar, it will be obvious, of course, that some of the brushes may be removed or that rotatably mounted brushes 18 might be replaced by stationary 15 brushes of other shape. It will also be obvious that one pair of brushes 22 may be sufficient to feed a cigar through the machine, although it is desirable to provide a pair of brushes such as shown, in order to insure a 20 thorough brushing of the surface of the cigar.

The differential rotation of brushes 22 and 24 insures relative movement of the brushes and the cigar during its passage through the 25 machine. While such differential movement might be produced by driving brushes 22 faster than brushes 24, it is desirable to drive the brushes 24 at a greater rate of speed since the machine is thereby cleared of a cigar prior 30 to the passage of another cigar therethrough, thus preventing contact of successive cigars.

What is claimed is:—

1. A machine for brushing cigars including a brush, and means for relatively moving 35 the cigar and brush during contact with each other.

2. A machine for brushing cigars including a brush, and means for moving a cigar longitudinally past said brush during contact 40 therewith.

3. A machine for brushing cigars including a brush and yielding means for moving a cigar past said brush and in contact therewith.

4. A machine for brushing cigars including a brush and means for moving a cigar past 45 said brush and in contact therewith, said means including a rotating brush.

5. A machine for brushing cigars including a plurality of rotating brushes arranged 50 to feed a cigar therebetween.

6. A machine for brushing cigars including a stationary brush, and a plurality of rotating brushes arranged to feed a cigar therebetween 55 past and in contact with the stationary brush.

7. A machine for brushing cigars including a stationary brush, a plurality of rotating brushes arranged to feed a cigar therebetween 60 past and in contact with the stationary brush, and means for guiding the cigar into proper engagement by the brushes.

8. A machine for brushing cigars including a plurality of pairs of rotating brushes, one 65 pair being driven at a speed different from

that of the other pair to brush a cigar fed thereto.

9. A machine for brushing cigars including a brush, and means for guiding a cigar into contact with the brush, said guiding means 70 and brush being relatively adjustable whereby selected portions of the brush may be subjected to contact with a guided cigar.

In testimony of which invention, I have hereunto set my hand, at Philadelphia, on 75 this 28th day of Dec., 1927.

KENNETH LYLE.
